UNITED STATES PATENT OFFICE.

SIMEON H. LA PLANT, OF SALIDA, COLORADO, ASSIGNOR TO THE L. T. N. MANUFACTURING & DEVELOPMENT SYSTEM, OF PLATTEVILLE, COLORADO, A COMMON-LAW TRUST.

CARBURETION SYSTEM FOR INTERNAL-COMBUSTION ENGINES.

Application filed July 27, 1925. Serial No. 46,358.

My invention relates to carburetion systems for internal combustion engines and its main object is to provide a system of the above character in which a highly efficient and wholly combustible gaseous explosive mixture is produced by the intermixture of a gasified fuel oil, air and exhaust gases obtained in the operation of an explosion engine.

Another object resides in providing a carburetion system which dispenses with the muffler ordinarily employed to deaden the sound of the escape of exhaust gases from the engine, another object is to provide a system which eliminates the use of a vacuum-tank, force pump or other similar contrivance to feed the hydrocarbonaceous liquid required in the explosive mixture, from a supply tank under pressure, and still another object resides in the construction of a mixing device or carburetor proper, in which a fuel of the above described mixture of gaseous components is produced without the use of floats, spring-valves and other complicated and easily deranged appliances of the type usually employed in apparatus for charging a gas with volatilized hydrocarbons in the operation of an internal combustion engine.

Other objects of the invention, mostly residing in details of construction and a novel arrangement of the elements and parts comprised in the system, will fully appear in the course of the following description made with reference to the accompanying drawings.

In the drawings in which similar characters of reference designate corresponding parts throughout the several views,

Figure 1 represents in outline, a partially sectional view of the arrangement of the mixing chamber, conduits, valves and other parts comprised in my improved carburetion system;

Figure 2, an enlarged sectional elevation of the carburetor or mixing chamber of the system;

Figure 3, a section taken on the line 3—3, Figure 2;

Figure 4 a sectional view showing in detail one of the check valves employed in the system;

Figure 5 a sectional view of the "choke valve" used to temporarily enrich the mixture in starting the engine;

Figure 6 a fragmentary elevation illustrating a modified construction of the discharge end of the exhaust line of the engine; and

Figure 7 a fragmentary elevation of the engine, mixing chamber and contiguous conduits, showing a modification in the arrangement thereof.

Referring further to the drawings, the numeral 5 designates the cylinder body of an internal combustion engine of the type used on motor-driven vehicles, provided as usual with an intake manifold 6 and an exhaust manifold 7. The carburetor of the system best shown in Figures 2 and 3, consists of a simple T-shaped pipe fitting 8, which constitutes the chamber in which the gaseous explosive mixture is produced. The hydrocarbonaceous fuel oil obtained from a supply tank 9, is admitted to the mixing chamber through a conduit 10 under control of an adjustable needle-valve 12.

The valve is seated in a housing 13 which is screwed into an aperture of the T-piece of which the carburetor is composed, and it is in the operation of the engine adjusted from a point adjacent the driver's seat of the vehicle, by a rotary forked rod 14 or other suitable means.

Air enters the mixing chamber by the suction of the engine, through a nozzle 15 fastened at an end of the T-piece by a reducing connection 16. The nozzle 15 is constantly open and no valve is required to regulate the admission of air to the mixing chamber under ordinary conditions.

The exhaust-gases used in the production of the explosive mixture are admitted to the mixing chamber by a pipe 17 connected at one end in the exhaust line of the engine and attached at its other end, to one of the branches of the T-piece by means of a reducer 18.

The connection between the portion 19 of the exhaust line leading from the manifold 7, and the conduit 17 is established by means of a reducer 20 and the continuation of the line beyond the point at which the pipe 17 is connected therein consists of a pipe 21 which is of smaller diameter than the main part

of the line, but which preferably is of greater diameter than the branch pipe 17 leading to the mixing chamber.

The proportionate sizes of the parts of the exhaust line may be varied in accordance with the quantity of burnt gases required in the mixture, it being the principal object of the reductions to divide the flow of gases exhausted from the engine, between the 10 branch pipe connected with the carburetor and the part of the line through which the gases escape into the atmosphere.

In the construction illustrated in the drawings the diameter of the continuation-pipe 15 21 is about one half that of the main conduit 19 connected with the manifold 7, and approximately twice that of the branch pipe 17 leading to the mixing chamber, and, owing to the fact that the flow of gases 20 through the branch pipe is constantly stimulated by the suction of the engine, the above stated ratio of diameters will cause the gases to be divided approximately equally between the pipe 21 and the pipe 17.

25 A check valve 22 in the pipe 17 prevents the return flow of the gases under the pulsating effect produced in the operation of the engine and a choke-valve 23 in the pipe 21 serves to increase the quantity of exhaust 30 gases admitted to the mixing chamber for the purpose of enriching the mixture when the engine is first started. The choke-valve may be adjusted by the driver of a vehicle by means of a rod 24.

35 It is preferred to connect the pipe 17 with the carburetor at a point immediately below that at which the fuel-oil enters the mixing chamber past the needle valve, and the reducer 18 by which the pipe 17 is connected 40 to the respective branch of the T-piece 8, is cup-shaped as shown in the drawings to retain the oil dripping from the superposed inlet after the operation of the engine is discontinued. In order to retain this liquid 45 in the cup-shaped container while the engine remains at rest the pipe 17 connected at the lower end thereof is bent in goose-neck form to provide a trap 25 as shown in Figures 1 and 7.

50 The connection between the carburetor and the intake manifold 6 of the engine is established through the medium of a pipe 26 connected with a branch of the T fitting of which the carburetor is composed, by 55 means of a reducing connection 27. The reducer 27 provides a housing for the butterfly valve 28 by means of which the admission of fuel to the cylinders of the engine is controlled; and it furthermore provides a secondary mixing chamber owing 60 to the momentary retardation of the flow before it enters the smaller conduit by which the reducer is connected with the manifold. The butterfly valve which controls the flow of fuel-mixture to the engine

and the needle valve regulating the supply of fuel-oil to the carburetor may be simultaneously adjusted at a predetermined ratio by suitable motion transmitting means such as the gear wheels 29 and 30 shown in the drawings.

A conduit 31 connects the fuel-supply tank 9 with one of the cylinders of the engine for the purpose of subjecting the liquid in the tank to pressure when the engine is 75 in operation. A check valve 32 in the conduit prevents the return flow of gases during the suction stroke of the piston in the cylinder with which the conduit is connected, and the two conduits 10 and 31 connected with the tank are provided with hand-valves 33 and 34 to regulate the flow of fluids to and from the same. In the operation of the system, the engine may be started at any time by means of the fuel-oil 85 stored in the priming cup 18, with the result that the liquid in the supply tank is immediately subjected to pressure by the gases exhausted from the cylinder with which the conduit 31 is connected, during 90 the up-strokes of the respective piston.

The pressure thus produced and maintained in the tank, causes the liquid contents of the tank to be fed to the mixing chamber where it meets the exhaust gases supplied through the pipe 17 and air drawn in by suction of the engine through the nozzle 15. The three components being thus brought in violent contact with each other within a restricted space, form a gaseous fuel which passes to the intake manifold of the engine through the conduit 26, it being evident that owing to the agitative velocity and the high temperature of the exhaust gases the hydrocarbon liquid supplied to the mixing chamber from the tank is completely volatilized before the mixture is delivered to the cylinders of the engine. 100

The volatilization and thorough intermixing of the three ingredients of the mixture are furthermore promoted by the secondary agitation that takes place in the butterfly valve-chamber 27 by reason of the temporary retardation of the stream of fuel drawn to the intake manifold, before entering the reduced conduit 26 by which it leaves the valve-chamber. The supply of liquid fuel from the tank and the admission of gaseous fuel to the intake manifold are readily regulated by adjustment of the valves 12 and 28, which if connected for conjunctive movement as in the construction shown in the drawings, proportion the discharge and supply to and from the carburetor at a predetermined ratio. 110

125 It will thus be observed that the operation of the engine is under constant control of the driver of the vehicle, the same as in carburetion systems used heretofore and that owing to the provision of the priming cup 130

18 and the connection 31 between the supply tank and a cylinder of the engine, the engine may be started and the liquid contents of the tank fed constantly to the carburetor without the vacuum tanks, pumps or other pressure-appliances at present employed for the same purpose. It will also be apparent that owing to the use of a considerable portion of the exhaust gases in producing the fuel for the operation of the engine and the consequent reduced discharge of exhaust gases into the atmosphere, the use of a muffler or other sound-deadening device may be dispensed with.

15 In case the quantity of exhaust gases drawn into the mixing chamber is not sufficient to entirely eliminate the noise produced by the escape of gases at the end of the exhaust line, a further reduction in the cross-sectional area of the line may be made as illustrated in Figure 6 in which a pipe-fitting 35 divides the course of the gases between two outlets 36 of reduced diameter.

20 The merits of exhaust gases of an internal combustion engine in producing an explosive fuel for the operation of the engine are well known, and the advantages of the present system reside chiefly in that the components of the fuel of which the exhaust gases are a part, are thoroughly intermixed in a finely divided condition completely volatilized and preheated to a high temperature before the fuel enters the intake of the engine, in an automatic operation of a system 25 of cooperating elements so simple in construction and arrangement, that the cost of installation and maintenance is at a minimum and the dangers of faulty operation or incapacitation by derangement or incorrect adjustment of the elements are completely eliminated.

25 In the modified construction of the invention illustrated in Figure 7, a second charge of exhaust gases is admitted to the mixing chamber by a pipe 37 provided with a check valve 38. The pipe is connected in the exhaust line at a point distant from that at which the line is tapped to supply the initial charge of exhaust gases to the mixing chamber, and by further reduction in the diameter of the line at the point at which the second division is made, the quantity of gases that ultimately escapes into the open is still further lessened to dispense with the use of 30 a muffler.

35 The second charge of exhaust gases to the carburetor, aids in the volatilization of the liquid fuel oil and in maintaining the mixture at the desired temperature and further enriches the mixture.

40 The pipe 31 by which the required pressure-fluid is conveyed to the supply tank, is preferably connected with one of the cylinders of the engine by means of the opening originally occupied by one of the priming

45 cups 39 but it is to be understood that any other connection may be made to produce a pressure in the tank, by and during the operation of the engine. Other modifications in the construction and the arrangement of the parts comprised in the improved carburetion system as herein described, may be resorted to without departing from the spirit and scope of the invention.

50 Having thus described my invention, what I claim and desire to secure by Letters Patent is:

1. In combination with an internal combustion engine, a fuel tank, a carburetor for supplying the fuel to the internal combustion engine having a restricted mixing space and provided with an air inlet and connected separately with the fuel tank and with an exhaust port connection of the engine, the exhaust port connection being located opposite the fuel inlet and the air inlet being located at an intermediate point between the fuel inlet and the exhaust port, and a priming cup in the exhaust port connection through which the exhaust gases pass.

55 2. In combination with an internal combustion engine, a source of hydrocarbon liquid, a carburetor having a restricted mixing space provided with an air-inlet and connected separately with the source and with the exhaust line of the engine at a point beyond the exhaust manifold and at different points in the exhaust line, and a connection between the mixing space of the carburetor and the intake of the engine.

60 3. In combination with an internal combustion engine, a source of hydrocarbon liquid, a carburetor having a restricted mixing space provided with an air-inlet and connected separately with the source and with the exhaust line of the engine at a point beyond the exhaust manifold and at different points in the exhaust line, the line being beyond each point of connection with the mixing space of the engine, reduced in diameter 65 to divide the flow of gases between the mixing space and the atmosphere at a determinate ratio, and a connection between the mixing space of the carburetor and the intake of the engine.

65 4. In combination with an internal combustion engine, a fuel tank, a carburetor for supplying the fuel to the engine having a mixing space connected separately with the fuel tank and with an exhaust port of the engine, a secondary mixing chamber located at one side of the carburetor and connected with an outlet of the first mixing space and provided with an outlet of reduced area, an air inlet at the opposite side of the carburetor, the fuel tank connection being at the top of the carburetor and the exhaust connection being at the bottom of the carburetor and having a priming cup through

which the exhaust gases pass, and a connection between the outlet of the secondary mixing chamber and the intake of the engine.

5. In combination with an internal combustion engine, a fuel tank, a carburetor having a mixing space connected separately with the fuel tank and with an exhaust port of the engine, the connection with the fuel tank being at the top of the carburetor and with the exhaust port being at the bottom of the carburetor and having a priming cup through which exhaust gases pass, a secondary mixing chamber located at one side of the carburetor and connected with an outlet of the mixing space and provided with an outlet of reduced area, a valve controlling the flow of gases between the outlets, an air inlet located at the opposite side of the carburetor at an intermediate point between the fuel connection and the exhaust connection.

6. In combination with an internal combustion engine, a source of hydrocarbon liquid, a carburetor connected separately with the source of liquid and with a source of exhaust gases, a connection between an outlet of one side of the carburetor and the intake of the engine, a valve controlling the admission of hydrocarbons to the carburetor, an air inlet at the opposite side of the carburetor, a valve controlling the discharge of fuel through the outlet of the carburetor, and means for the conjoint operation of the valves at a determinate ratio.

7. In combination with an internal combustion engine, a fuel tank, a carburetor for supplying the engine with fuel connected with the fuel tank, a priming cup in the connection located at the bottom of the carburetor and forming an extension of the same, and in a connection between the carburetor and the exhaust of the engine, said priming cup being adapted to retain a

quantity of liquid, and a connection between the outlet of the carburetor and the intake of the engine.

8. In combination with an internal combustion engine, a fuel tank, a carburetor connected separately with the tank and with a combustion space of the engine for the supply of exhaust gases, a priming cup arranged at the bottom of the carburetor and forming an extension of the same, said priming cup being in a connection between the exhaust of the engine and the carburetor and adapted to retain a quantity of liquid, and a connection between the outlet of the carburetor and the intake of the engine located at one side of the carburetor, the latter being provided at the opposite side with an air intake opening.

9. In combination with an internal combustion engine, a fuel tank, means for connecting the fuel tank with one of the cylinders of the engine for producing pressure in the fuel tank, and a carburetor connected at the top with the fuel tank and with the engine and having an extension at the bottom forming a priming cup, said priming cup being arranged in a connection between the carburetor and the exhaust of the engine.

10. In combination with an internal combustion engine, a source of hydrocarbon liquid, a carburetor comprising a T-pipe, an opening of which is connected with an intake of the engine, a nozzle connected in a second opening of the T-pipe for the admission of air, a priming cup connected at the third opening of the same, in connection with the exhaust of the engine, and a connection between the T-pipe and the source located above the priming cup.

In testimony whereof I have affixed my signature.

SIMEON H. LA PLANT
